ATTORNEY

UNITED STATES PATENT OFFICE

JAMES O. LEWIS, OF TULSA, OKLAHOMA

COMPRESSOR CYLINDER

Application filed June 10, 1929. Serial No. 369,582.

My invention relates to air and gas compressors and has for its principal object to obviate the loss in efficiency of such devices ordinarily incident to distortion of the valves by heat of compression and to drop in pressure incident to cooling of the compressed medium after it leaves the compressor.

In accomplishing this and other objects of the invention, I have provided improved details of structure, the preferred forms of which are illustrated in the accompanying drawings, wherein:

Fig. 1 is a central longitudinal section through the cylinder illustrating the improved means for cooling compressed gases therein.

Fig. 2 is a transverse section through the cooling means on the line 2—2, Fig. 1.

Referring in detail to the drawings:

1 designates a double acting compressor cylinder including a body member 2 having a compression or piston chamber 3 fitted with a piston 4 and rod 5 and surrounded by double side walls 6 and end wall 7 enclosing a cooling chamber 8 supplied with cooling medium through an inlet pipe 9 and having an open end 10 provided with a removable head 11, the side walls being provided with openings 12 in their bottom side and at opposite ends thereof fitted with intake valves 13 communicating with the compression chamber and with an intake manifold 14.

Formed on the end wall 7 is an apertured flange 15 for mounting the cylinder on an engine frame, and extending through the wall concentric with the compression or piston chamber 3 is a bearing sleeve 16 slidably engaged by the rod 5 which extends through a valve housing 17 secured on the outer side of the wall 7 and has a packing gland 18 sealingly engaging the rod.

Provided in the end wall 7 in radial spaced relation with the bearing sleeve 16 are channels 19 forming clearance space additional to that in the compression or piston chamber 3 and constituting elongated ports extending through the cooling chamber 8 and connecting the inner end of the compression or piston chamber 3 with the chamber of the valve housing 17, containing a valve 20 controlling

flow through the ports and valve chamber to an outlet pipe 21 leading to a pressure flow line, (not shown).

The cylinder head 11 is sealingly secured to the open end 10 of the body member 2 by a gasket 22 and bolts 23, and includes spaced double walls 24 forming a cooling space 25 having communication with the cooling chamber 8 and provided with an outlet pipe 26.

Extending through the walls 24 in circular formation are channels or elongated ports 27 also forming extensions of the clearance space at that end of the cylinder and connecting the outer end of the compression or piston chamber with the chamber of a valve housing 28 on the outer side of the head, containing a valve 29 for controlling flow through the ports and valve chamber to an outlet pipe 30 for connection with a pressure flow line, (not shown).

With the compressor in operation reciprocation of the piston in the compression or piston chamber 3 causes charges of gases to be alternately drawn through the intake valves 13 into opposite ends of the chamber and compressed by opposite strokes of the piston.

When the piston moves rearwardly in the cylinder as indicated by arrows, the inlet valve at the rear end of the cylinder is closed and gases in the opposite end of the cylinder are compressed and forced through the ports 19, wherein the compressed gases are cooled by the cooling medium in the chamber 8 previous to contact with the discharge valve and their ejection into the outlet pipe 21.

Gases drawn into the forward portion of the compression or piston chamber during the rearward stroke of the piston are compressed during the forward stroke, forced through the ports 27 and cooled therein by the cooling medium in chamber 8 previous to contact with the discharge valve 29 and ejection into the outlet pipe 30.

Thus it is apparent that, with my improved cylinder, the compressed gases are cooled before they reach the discharge valve, thereby avoiding distortion of the valve and resultant loss of control of the gases, and that by

cooling the gases prior to their leaving the cylinder, drop in pressure incident to cooling may be compensated for in the piston stroke to insure discharge of the gases from the cylinder at desired working pressure.

What I claim and desire to secure by Letters Patent is:

1. A compressor cylinder including a piston chamber and channels leading from said chamber and providing additional clearance space for said chamber, and a valve adapted to seat on the outer ends of the channels, the cylinder having cooling space about the channels.
2. A compressor cylinder including a piston chamber and a plurality of spaced channels leading from said chamber and providing additional clearance space for said chamber, and a valve adapted to seat on the outer ends of the channels, the cylinder having space for travel of cooling fluid about the channels whereby compressed fluid is cooled before leaving said clearance space.
3. A compressor cylinder having a surrounding cooling chamber and including a hollow head member having communication with said cooling chamber and having channels therethrough providing elongated discharge ports, a valve adapted to seat on the outer ends of said ports, and means for effecting flow of cooling medium through the cooling chamber and about said ports.
4. A compressor cylinder including a surrounding cooling chamber and a hollow head member having communication with said chamber and having an annular series of channels therethrough providing elongated discharge ports, an annular valve adjacent the outer ends of the ports and means for urging said valve into seating engagement with said ports at the outer ends of said channels.
5. A compressor cylinder having a surrounding cooling chamber and including a hollow head member having communication with said cooling chamber and having an annular series of channels therethrough providing elongated discharge ports, an annular valve adjacent the outer ends of the ports, means for urging said valve into seating engagement with said ports at the outer ends of the channels, a valved inlet for the cylinder, a piston in the cylinder and means for effecting flow of cooling medium through the cooling chamber and about said ports.

In testimony whereof I affix my signature.
JAMES O. LEWIS.
